(57) **CLAIM**

The ornamental design for an earbud and charger case, as shown and described.

DESCRIPTION

FIG. 1 is a perspective view of the charger case, of an earbud and charger case showing my new design; the charger case is shown separately for ease of illustration;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a perspective view of an earbud of the earbud and charger case, shown separately for ease of illustration;
FIG. 10 is another perspective view thereof;
FIG. 11 is a front elevational view thereof;
FIG. 12 is a rear elevational view thereof;
FIG. 13 is a left side elevational view thereof;
FIG. 14 is a right side elevational view thereof;
FIG. 15 is a top plan view thereof;
FIG. 16 is a bottom plan view thereof;
FIG. 17 is a front elevational view of an earbud and charger case in an open position thereof; and,
FIG. 18 is a side perspective view of an earbud and charger case in an alternate position thereof.

The broken lines in the drawings depict portions of the earbud and charger case that form no part of the claimed design.
